FIG. 1 is a top, front, right-side perspective view of a bag securing member embodying our design, the bag securing member being disposed on a frame member;

FIG. 2 is a top, front, right-side perspective view thereof;

FIG. 3 is a front elevation view thereof;

FIG. 4 is a rear elevation view thereof;

FIG. 5 is a right-side elevation view thereof, the left-side elevation view being a mirror image of the right-side elevation view;

FIG. 6 is a top plan view thereof; and,

FIG. 7 is a bottom plan view thereof.

The broken line showing in FIG. 1 is included for the purpose of illustrating environment and forms no part of the claimed design.
